E. L. AIKINS

FLUID CONVEYER SYSTEM

Filed June 4, 1927

UNITED STATES PATENT OFFICE.

EDWARD L. AIKINS, OF SEATTLE, WASHINGTON.

FLUID-CONVEYER SYSTEM.

Application filed June 4, 1927. Serial No. 196,595.

This invention relates generally to improvements in fluid conveyer apparatus and more particularly to means for feeding or charging material into conveyer systems of this type.

Fluid conveyers of the type to which the present invention relates comprise broadly a conduit extending between one or more charging stations and one or more receiving stations and through which fluid under pressure, such as compressed air, is caused to flow at a relatively high velocity so that granular, fibrous, powdered or similar material fed into the conduit at a charging station is entrained in the fast flowing stream of compressed fluid and carried thereby through the conduit to a receiving station where there may be provided suitable means for separating the solid material from the conveyer fluid. While apparatus for this general purpose has long been known and used, they have for the most part been somewhat handicapped in that no adequate means was provided for charging the materials into the conveyer conduit at a substantially uniform rate, and in the absence of such means the systems frequently became over-loaded causing sluggish operation and often resulting in a complete clogging of the conduit. This was due in the main to the fact that the material was supplied to the system in "slugs" or batches.

The present invention therefore has in mind the provision of means for charging material into the conveyer conduit at a substantially uniform rate and in a manner such as to substantially preclude the possibility of overloading or clogging the system.

A further object of the invention is to provide means for positively regulating and controlling the rate of charging in accordance with the character of the material to be handled, thereby adapting the apparatus to efficient use in connection with many different industries.

Another object of the invention is to provide an apparatus of the type indicated which is especially useful in handling and conveying saw mill refuse but which may also be advantageously used for handling pulverized coal, grain, ashes, paper trimmings, rags and similar comminuted material.

The invention consists in certain new and improved features of construction and combination of parts hereinafter fully described in the specification and illustrated in the

accompanying drawings and which are pointed out more particularly in the appended claims.

In the accompanying drawings, wherein I have illustrated a preferred embodiment of my invention,

Fig. 1 is an elevation of a complete conveyer system.

Fig. 2 is a sectional view taken on the line 2—2 of Fig. 1.

Fig. 3 is a sectional view taken on the line 3—3 of Fig. 2.

Fig. 4 is a sectional view taken on the line 4—4 of Fig. 3.

Fig. 5 is a fragmental detail view partly in section showing one form of nozzle adjusting means.

Fig. 6 is a detail view of a modified form of nozzle.

Referring more particularly to the accompanying drawings wherein like reference numerals designate like parts throughout, 1 indicates any convenient bin or source of supply for the material to be handled. Immediately beneath the bin 1 is a receiving chamber or hopper 2 having communication with a suitable conveyer conduit 3. Compressed air or other fluid is passed through the conduit 3 from any convenient source of supply, such as a blower or compressor indicated at 4. The conduit 3 communicates at its discharge end with a suitable separating apparatus 5 designed to effect the separation of the conveying fluid and solid materials entering the same and to discharge the latter from a conveniently arranged spout 6.

As shown in Fig. 1, the compressed air or other fluid from the source indicated at 4 is supplied to the conduit system 3 by means of a pipe line 7 which extends through the side wall 8 of the receiving hopper 2 and terminates therein in a downwardly directed portion 9 arranged centrally of said chamber and in axial alignment with the conduit 3. The downwardly directed portion 9 of the pipe 7 terminates in a discharge nozzle 10, the orifice 11 of which is controlled by a needle valve 12. The valve 12 carries an elongated operating stem 13 which extends axially of the pipe portion 9 through the curved upper wall thereof into screw-threaded engagement with an integral boss or nipple 14 and terminates in a suitable hand wheel 15.

The receiving hopper 2 is substantially

cylindrical throughout the major portion of its length but as shown in Fig. 3 tapers downwardly forming a substantially conical lower portion 2^a merging into a contracted 5 throat or venturi 16 surrounding and adjacent to the discharge nozzle 10, thus defining an annular supply passage for the material from the chamber 2 into the venturi. The venturi 16 terminates in a lower cylindrical portion 17 which telescopically engages a sleeve member 18 secured to the end of the conveyor conduit 3.

It is, of course, obvious that the pressure of the conveying fluid may be capable of 15 variation within suitable limits and that the volume of air admitted to the apparatus may be adequately controlled by means of the valve mechanism 12 hereinbefore referred to, but in order to adapt the apparatus to use 20 with materials of different characters and to insure at all times a maximum degree of vacuum with a given volume and pressure of conveying fluid, it is desirable to adjust the relative position of the discharge nozzle 25 10 with respect to the throat of the venturi 16. This adjustment is preferably effected by bodily raising or lowering the hopper 2 which is made possible by the provision of 30 an elongated slot 19 in the wall of the receiving hopper through which extends the delivery or discharge end of the compressed air line 7. The slot 19 is of a length sufficient to permit the necessary range of movement 35 of the hopper 2 with respect to the nozzle 10 in order to provide for the necessary range of adjustment between the nozzle and the venturi, and the unoccupied portions of 40 said slot are covered by the shield or guard 20 surrounding the pipe 7 and arranged to move in spaced confining guides 21 secured to the outer wall of the hopper 2 on either side of the slot. This construction is clearly illustrated in Figs. 2 and 3.

The adjustment of the nozzle with respect 45 to the venturi is realized by varying the effective length of the hopper support by altering the degree of telescopic engagement between the lower cylindrical portion 17 of the venturi and the sleeve 18, the latter being 50 fixed to the conduit 3. These elements may be retained in an adjusted position by means of a clamping band or strap 22 carried by the sleeve 18 adjacent to its upper extremity and while this adjustment may be made in 55 any convenient manner and without the instrumentality of any mechanical devices, I prefer to provide suitable cooperating members on the sleeve 18 and the hopper structure for the purpose of effecting said adjustments. 60 Such means are shown in Figs. 2 and 3 as comprising gears or pinions 23 and 23^a rotatably mounted upon the lower cylindrical portion 17 of the hopper structure and arranged to operatively engage suitable racks 65 24 formed in longitudinal walls of an elongated

slot in the wall of the sleeve 18. The pinions 23 and 23^a are preferably mounted to rotate upon studs or pins 26 fixedly secured to the wall of the cylinder 17 and the pinion 23 is provided with a squared boss 70 27 to permit the application thereto of a suitable crank or operating handle 28. Thus the pinion 23 may be rotated upon the stud 26 and due to the engagement between the gears and racks the hopper structure will be 75 adjusted vertically up and down according to the direction of rotation of said pinion. Incidentally it may be noted that the shifting of the nozzle 10 with respect to the venturi 16 serves also to vary the area of the annular 80 material supply passage between the nozzle and the conical wall 2^a of the hopper.

A modified form of adjusting mechanism is shown in Fig. 5, wherein the sleeve 18 is provided with an outstanding lug 29 having a screw-threaded aperture 30 adjacent its free extremity. The chamber structure is provided with a divided yoke or strap 31 clamped about the throat 16 and carrying a vertically disposed and freely rotatable 90 threaded operating rod 32 at its extremity. The rod 32 is in vertical alignment with the threaded aperture 30 of the lug 29 into which it is threaded. Suitable thrust collars 33 are provided on opposite sides of the yoke 31 so that by rotating the rod 32 through the instrumentality of a suitably provided hand wheel 34 the hopper structure may be shifted vertically with respect to the sleeve 18 to properly position the nozzle 10 with 100 respect to the venturi 16. It is to be noted that the sleeve 18 if desired may be split longitudinally in a conventional manner to facilitate the clamping and unclamping of the sleeve 18 and the cylindrical portion 17 105 of the hopper.

In order that the operator may be apprised of the relative position of the parts, a suitable scale or indicator is provided in the form of a series of calibrations or graduations 35 inscribed upon one of the shield or guide members 21, and which are designed to cooperate with an indicating hand 36 inscribed on the shield 20. It is, of course, obvious that if desired, similar indications 110 or calibrations may be arranged upon one wall of the cylinder 17 and the sleeve 18 adjacent the wall of the slot 25 as shown in Fig. 2.

In Fig. 6, I have shown a slightly modified 120 form of nozzle having an elongated tapered portion 10^a terminating in a substantially cylindrical discharge portion 10^b, the latter functioning under certain conditions to effect a more uniform feed of the material 125 from the chamber 2 into the conduit.

In operation, material such as saw mill refuse is allowed to pass from the bin 1 into the receiving hopper 2, a suitable valve (not shown) being preferably arranged in the 130

discharge spout of the bin for controlling the passage of material therefrom. The material thus supplied to the hopper 2 falls around the portion 9 of the pipe 7 and passes over the conical wall of the chamber 2^a. The compressed air or other fluid discharging from the nozzle 10, due to the action of the venturi 16, creates an area of low pressure surrounding said nozzle and to the rear 10 thereof which effects a uniform pull or suction upon the material passing therethrough with the result that said material is forcibly sucked into the venturi 16 at a substantially uniform rate. In the event of the material 15 being supplied to the hopper 2 from the bin 1 in quantities in excess of the amount which will pass readily through the annular supply passage between the nozzle 10 and the conical wall 2^a, said material may accumulate 20 to the rear and above the nozzle in which event the high vacuum resulting in this portion of the chamber will function to maintain a positive and uniform feed of the material into the venturi. As the material 25 passes through the venturi throat it becomes entrained in the stream of conveying fluid and is driven along by the same at a high velocity through the conduit 3 to the separating apparatus 5 from which it is dis- 30 charged through the spout 6.

From the foregoing description, it is apparent that by arranging the air discharge nozzle above the end of the conveyer conduit and coaxial therewith, and by interposing between these elements the movable receiving chamber terminating in a Venturi tube adjacent to the discharge nozzle, I have provided a simple, convenient, and highly efficient feeding apparatus which will deliver the material into the conduit longitudinally thereof or in the direct line of travel of the air stream therein. Also, by means of the injector nozzle and venturi action I am able to insure a positive and uniform feeding of the material without danger of overloading or clogging of the conveyer conduit. Furthermore, by reason of the relative adjustability of the nozzle and venturi the apparatus is capable of producing a maximum degree of vacuum for any given pressure and volume of conveying fluid being supplied to the apparatus and is therefore efficient, in handling materials of widely differing characteristics, it being incidentally noted that this adjustment serves not only to vary the degree of suction produced in the area surrounding and to the rear of the discharge nozzle, but that it also serves to alter the area of the annular space between the nozzle and conical wall of the chamber through which the material being handled passes into the conduit system. It is, therefore, apparent that by the combined needle valve control of the air jet and the relative

adjustability of the jet itself with respect to 65 the venturi, I have provided a very efficient and practical feeding apparatus, which, due to its highly flexible regulation and control is capable of a variety of adaptations not heretofore practicable with fluid conveyer 70 systems.

In conclusion, it is to be noted that while I have here illustrated and described certain preferred embodiments of my invention, such illustrations and description are for 75 the purpose of example only and are not to be construed as defining or limiting my invention, as such definitions and limitations are to be determined from the scope of the appended claims. 80

Having thus described my invention, what I claim as new, is:

1. In a fluid conveyer system, the combination with a conveyer conduit and means for supplying a conveying fluid thereto, said elements being fixed with respect to each other, of a relatively movable material receiving hopper interposed between the conduit and the fluid supply means, and means for shifting said hopper bodily with respect 85 to the fluid supply means for the purpose of regulating the rate of feed of material into the conduit. 90

2. In a fluid conveyer system, the combination with a conveyer conduit and fluid supply means therefor and relatively fixed with respect thereto, of a relatively adjustable material receiving hopper surrounding the fluid supply means and having communication with the conduit, and cooperative 100 means carried by the receiving hopper and conduit for shifting said hopper bodily with respect to the fluid supply means whereby to effect a regulation of the rate of feeding material into the conduit. 105

3. A material feeding apparatus for fluid conveyer systems comprising a material receiving hopper having communication with a conveyer conduit and adjustably mounted with respect thereto, said hopper having a substantially conical throat, a fluid pressure line terminating within the hopper in a discharge nozzle positioned within said conical portion of the hopper, and operating means cooperatively engaging the hopper and conduit for bodily moving the hopper with respect to the discharge nozzle to regulate the pressure within the conical throat and the rate of feed of the material from the hopper. 110 115

4. A material feeding apparatus for fluid conveying systems comprising a material receiving hopper having communication with a conveyer conduit, a fluid pressure line extending through the wall of the hopper and terminating therein in a discharge nozzle, 120 and means to shift the hopper with respect to the nozzle to regulate the rate of feed of the material from said hopper, the wall of the 125

hopper being slotted to permit said shifting, and a plate covering the unoccupied portions of said slot.

5. A material feeding apparatus for fluid conveyer systems comprising a fixed supporting sleeve, a material receiving hopper telescopically engaged therewith, and having communication with a conveyer conduit, a fixed fluid pressure line terminating within 10 the hopper in a discharge nozzle, the hopper adjacent to the nozzle being contracted to form a regulatable material supply passage around the nozzle, and cooperative means carried by the hopper and sleeve for 15 effecting a relative adjustment between the hopper and nozzle to regulate said supply passage.

6. The apparatus described in claim 5 wherein cooperative indicating means are 20 associated with the sleeve and hopper for indicating the relative position of the nozzle within the hopper.

7. The combination with a fluid conveyer system including a conduit, of a supporting sleeve secured thereto, a material receiving hopper telescopically engaged with the sleeve, a fixed fluid pressure pipe line extending centrally into the hopper, the hopper adjacent the nozzle being contracted to 25 form an annular supply passage around the nozzle and cooperative means interposed between the sleeve and hopper for shifting the hopper with respect to the nozzle to vary the size of the supply passage.

30 8. The apparatus described in claim 7 wherein means is provided for controlling the discharge of fluid from the nozzle.

9. A material feeding apparatus for fluid conveyer systems comprising a hopper, a 35 fluid pressure line extending into the hopper through a side wall thereof and terminating in a discharge nozzle, said hopper having a contracted discharge throat surrounding the nozzle, and means to shift the hopper bodily with respect to the fluid pressure line to vary the relative position of the nozzle and throat, the side wall of the hopper being slotted to permit shifting the 40 hopper.

50 10. A material feeding apparatus for fluid conveyer systems comprising a hopper, a fixed fluid pressure line extending into the

hopper and terminating in a discharge nozzle, the hopper adjacent to the nozzle being contracted to form a Venturi discharge passage, and means for bodily shifting the hopper to vary the pressure in the Venturi passage.

11. The apparatus described in claim 10 wherein means are provided for indicating 60 the relative position of the nozzle and venturi.

12. A material feeding apparatus for fluid pressure conveyers comprising a support, a hopper adjustably supported thereby, a fixed 65 fluid pressure line extending into the hopper and terminating in a discharge nozzle, the hopper having a discharge passage surrounding the nozzle, and means for adjusting the hopper with respect to the support 70 to thereby vary the relative position of the nozzle with respect to the discharge passage.

13. A material feeding apparatus for fluid conveyer systems comprising a hopper provided with a Venturi discharge passage, a 75 fluid pressure line extending into the hopper and terminating in a discharge nozzle within the venturi, an extensible support for the hopper, and means for varying the effective length of the support whereby to adjust the 80 nozzle with respect to the venturi.

14. The apparatus described in claim 13 wherein the extensible support for the hopper is a tubular member serving as a discharge conduit for the hopper. 85

15. A material feeding apparatus for fluid conveyer systems comprising a support, a hopper adjustably mounted upon the support, a fluid pressure line extending into the hopper, and terminating in a discharge nozzle, the hopper adjacent the nozzle being contracted to form a Venturi discharge passage, and cooperative means carried by the hopper and support for adjusting the nozzle 90 with respect to the venturi, said means including a rotatable member carried by the hopper and operatively engaging the support, and means whereby the rotation of said element serves to shift the hopper bodily 95 with respect to the support. 100

In testimony whereof I hereunto affix my signature.

EDWARD L. AIKINS.
